UNITED STATES PATENT OFFICE.

EDWARD E. STOUT, OF INDIANAPOLIS, INDIANA.

STORAGE BATTERY.

1,250,696.

Specification of Letters Patent. Patented Dec. 18, 1917.

Application filed March 10, 1917. Serial No. 153,967.

To all whom it may concern:

Be it known that I, EDWARD E. STOUT, a citizen of the United States, residing at Indianapolis, Marion county, and State of Indiana, have invented and discovered certain new and useful Improvements in Storage Batteries, of which the following is a specification.

My invention relates to storage batteries.

10 The objects of the invention are to provide means to equalize the distribution of the lines of force of the current through the battery elements; to obtain such distribution in shorter curves than is possible with 15 the usual construction; to lessen the internal resistance; to render it possible to employ a smaller number of elements than usual in a battery of the same capacity; to decrease the heat produced by the current; and to 20 also equalize the temperature throughout the plate; to equalize the distribution of the gases generated; to prevent the burning out of the plates; to prevent buckling of the 25 plates under excessive charges or because of other conditions; and to provide means for accomplishing the foregoing ends which shall be capable of more effectively supporting the plates than the present construction in use.

30 With the above objects and others in view, my invention embodied in preferable form in the construction and arrangement hereinafter described and illustrated in the accompanying drawings.

35 In these drawings, Figure 1 is a longitudinal vertical section through a battery cell showing one of the plates and the connector; Fig. 2, a section at right angles to Fig. 1, and Fig. 3, a detail end perspective 40 of the connector-carrying core.

Referring to the drawings, 1 constitutes an end plate of the set of positive plates and which is provided with an exterior terminal connecting lug 2 of the usual construction. 45 adapted to receive the terminal stud member 3. 4 indicates the end plate of the negative series which is provided with a terminal lug 5 of the usual construction.

The intermediate positive plates are indicated by the numeral 6 and intermediate negative plates by 7. These plates are unprovided with the usual exterior terminal connecting and attaching lugs, and they are supported centrally thereof on a core 8 con-

stituting a connector carrier and also a support for the plates and which member constitutes the essential novel feature of my invention. This member is made of rubber or fiber or other suitable insulating material. It is formed with any suitable cross section 55 adapted to provide symmetrically disposed surfaces for the attachment of opposite connectors of the same polarity. In the particular form of the core here shown the same is rectangular in general outline with 60 recesses 9 and 10 formed therein respectively at angles of 90°. The recesses 9 are opposite one another and are adapted to receive longitudinal connector strips 11, which constitute the connectors for the positive plates, 65 while the recesses 10 receive the longitudinal negative connector strips 12. These strips are preferably of lead and they are adapted to make contact with terminal lugs 70 formed on the central portion of the grid 75 of the plate and extending into the recesses. These strips are respectively connected with the positive and negative plates at the ends of the cell. So far as the broad idea of the terminals located within the border of the 80 plate is concerned, of course connector means other than the longitudinal strips, 85 might be employed in connection therewith. The lead lugs 13 not only serve as means of electrical connection with the connector 90 strips but also as locking means to interfit with the irregular contour of the core so as to effectively retain the plates on the core in alined position.

Although the invention is not limited in 90 scope or practical application to the use of a plurality of connector strips for each set of plates, such arrangement is preferable and highly advantageous, since it enables the terminals or points of circuit connection, 95 to be positioned equidistantly from the center to thereby aid in effecting the equal distribution of the lines of force to all parts of the plate which is the primary object of the invention. The use of the pair of connector strips also, in coöperation with the core or supporting member, enables the necessary insulation between the positive and negative connectors and terminals to be effectively obtained.

In order to lessen the angularity of the lines of flow of the current the corners of the core are preferably rounded to permit of

a corresponding formation of the contacting part of the plate grid. The recesses 9 and 10 are preferably dovetailed or similarly narrowed at their outer ends to afford 5 more secure locking means and enable shallower recesses to be employed.

The plates are symmetrical in form and preferably square so that the positive plates when placed in position on the core will 10 have their terminal lugs so positioned that the same will connect with the upper and lower connector strips on the core while the negative plates are turned at right angles to the positive plates so that the contact lugs 15 thereof will engage with the connector strips which are at right angles to the positive connecting strips.

Between the adjacent positive and negative plates are placed separators 14 which 20 may be of any usual insulating material and any desired form.

It will be seen that by the above construction, the battery elements are supported at their centers and that the electrical terminal connections are also adjacent their centers whereby the current enters the plate near the center during charging and enters the borders during discharging and is distributed from said points 30 equally to all parts of the plate. The effect of this substantially radial traverse of the current is to decrease the length of the lines of flow, to reduce the angularity of the currents, to reduce inequalities in potential, 35 and, as a result of such functions, to prevent overheating and buckling of the plate, to prevent the undue generation of gas at the bottom of the cell and to enable the battery to be charged with currents of 40 greater amperage without danger of producing such buckling. Owing to the fact that the central portion of a battery plate is "dead" or substantially inactive, and the insulating support is confined to this area, 45 the entire remaining and active part of the plate is fully utilized, which is not the case when the connections are made at the top of the plates. Hence a smaller number of plates may be employed than is usual to 50 obtain a cell or battery of the same capacity. The central support of the plates also tends to aid mechanically in maintaining the form of the elements.

Having thus described my invention, 55 what I claim is:

1. A storage battery having elements comprising alternate positive and negative plates, side by side, and element terminals entirely within the borders of the elements.
- 60 2. In a storage battery, positive and negative plates arranged side by side and having the terminals thereof entirely within the borders of the plates and adjacent the centers of the latter to effect distribution of the current through the elements from the centers

thereof, and to receive the current entering the elements and thus direct the same equally from all surrounding portions of the elements to the centers.

3. A storage battery plate having a plurality of current receiving terminals thereof within the borders of the plate to distribute the current from the inner part of the plate outwardly. 70

4. A storage battery having electrically 75 connecting members for the positive and negative plates extending substantially centrally through said plates.

5. A storage battery having plates with a terminal member substantially adjacent 80 the center thereof and a connector member extending through the plates and having connection with said terminal members.

6. A storage battery having plates centrally apertured, and having a terminal lug 85 projecting from each plate inwardly toward the center in the plane of the plate, positive and negative connector members extending through said apertures and connecting with lugs of the respective positive and negative plates, and insulating means in said apertures separating said connector members. 90

7. A storage battery having a supporting member extending through the bodies of 95 the negative and positive elements thereof.

8. In a storage battery, in combination with positive and negative battery elements comprising plates arranged side by side, a common supporting member for said plates 100 consisting of a core of non-conducting material extending through the plates substantially centrally thereof and on which the latter are supported, and a plurality of connector strips for each set of plates carried by said core and extending longitudinally of the cell, each plate of each set having a plurality of terminals to connect with said connector strips. 105

9. In a storage battery, in combination 110 with battery elements, a core of non-conducting material extending through the said elements centrally thereof and on which the same are supported and connector strips carried by said core and extending longitudinally of the battery. 115

10. In a storage battery, in combination with battery plates, a core of non-conducting material extending substantially centrally through said plates and on which the latter are mounted, connector strips for the plates of one polarity mounted on opposite sides of said core and extending longitudinally thereof and connector strips for the plates of opposite polarity mounted on said core at substantially right angles to the strips of the other polarity. 120

11. In a storage battery, in combination with battery plates, a core of non-conducting material extending through said plates 125

centrally thereof and having recesses formed therein, a pair of connector strips for the plates of one polarity mounted in opposite recesses, and a pair of connector strips of opposite polarity mounted in the other opposite recesses, said plates having terminal contact lugs adapted to enter said recesses to connect with said strips.

In witness whereof, I have hereunto set my hand and seal at Indianapolis, Marion 10 county, Indiana, this 7th day of March, A. D. nineteen hundred and seventeen.

EDWARD E. STOUT. [L.S.]
